UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY CAR RETARDER

Application filed October 9, 1929. Serial No. 398,304.

My invention relates to railway car retarders of the type involving braking bars located in the trackway and movable into engagement with the wheels of a car for the purpose 5 of retarding the motion of the car.

One object of my invention is the provision in a car retarder of the type described of apparatus for positively guiding onto the rails at the leaving end of the retarder car 10 wheels which have been raised off of the rails in passing through the retarder.

I will describe one form of apparatus embodying my invention, and will then point out the novel features thereof in claims.

15 In the accompanying drawing, Fig. 1 is a top plan view showing a car retarder provided with one form of apparatus embodying my invention. Fig. 2 is a sectional view on the line II—II of Fig. 1.

20 Similar reference characters refer to similar parts in both views.

Referring to the drawing, the reference characters 1 and 1^a designate the track rails of a stretch of railway track, which track 25 rails are mounted on crossties 2 in the usual manner, and over which cars normally move from left to right as viewed in Fig. 1. Associated with the track rails 1 and 1^a is a car retarder, designated in general by the reference character A, and comprising two braking bars 3 and 4 located on opposite sides of the track rail 1, and two similar braking bars 3^a and 4^a located on opposite sides of the track rail 1^a. The braking bars may be moved 30 toward or away from the track rails, that is, into closed or open positions of the retarder, by any suitable means, such for example, as the mechanism shown and described in my co-pending application for Letters Patent of 35 the United States, Serial No. 307895, filed September 24, 1928, for railway braking apparatus. This mechanism is omitted from the drawing because it forms no part of my present invention.

40 In the operation of car retarders of the type described it may happen under some conditions that the wheels of a car, upon being engaged by the braking bars, are lifted off of the track rails and ride up on top of the braking bars. When this occurs, it is

desirable to guide the wheels of the car back onto the track rails at the leaving end of the retarder in order to prevent the wheels of the car from dropping down into the trackway and damaging the car and lading, or the 55 apparatus located in the trackway, or both. For this purpose, I provide two guide rails 5 and 7 which may be standard rail sections, and which, as here shown, are located between the track rails at the leaving end of the retarder with the guide rail 5 adjacent the track rail 1 and with the guide rail 7 adjacent the track rail 1^a. The guide rails are mounted on riser blocks 6 secured to the crossties 2. The thickness of the riser blocks is such that 60 the tops of the guide rails extend slightly above the tops of the track rails as best seen in Fig. 2. The guide rail 5 is bent intermediate its ends to form a long leg 5^a and a short leg 5^b, and the guide rail 7 is similarly 65 bent to form a long leg 7^a and a short leg 7^b. The left hand end of the leg 5^a of the guide rail 5 is located adjacent the end of the braking bar 3 and the rail 5 is so arranged that 70 both legs of the bar are inclined to the rail 1, sufficient clearance being maintained between the rail 1 and the guide rail 5 at their nearest point to permit the passage of a car wheel flange between the track rail and the guide rail. The left hand end of the leg 7^a of the 75 guide rail 7 is located adjacent the end of the braking bar 3^a, and the rail 7 is so arranged that both legs of the bar are inclined to the rail 1^a, while permitting a wheel flange to pass fully between the track rail 1^a and the 80 guide rail 7. Located between the track rail 1 and the leg 5^a of the guide rail 5 is a triangular plate 12, and located between the track rail 1^a and the leg 7^a of the guide rail 7 is a similar triangular plate 14. The plate 12 is fastened, by means of a plurality of 85 screws 12^a, to a block 13 which, in turn, is fastened to a tie 2 by means of a lag screw 18, the head of which fits in a suitable hole formed in the plate 12 and the top of the block 13 so that the head does not extend above the top of the plate 12. The plate 14 is similarly fastened by means of screws 14^a 90 to a block 15 which, in turn, is fastened to a tie 2 by means of a lag screw 19 in the same 95 100

manner as the block 13 is fastened to the tie 2 by the lag screw 18. The parts are so arranged that the upper surfaces of the plates 12 and 14 are parallel with the tops of the track rails 1 and 1^a but are located below the tops of the track rails a distance which is slightly less than the minimum depth of any car wheel flange.

Two other flat plates 8 and 10 extend parallel with and are in engagement with the track rails 1 and 1^a on the opposite side of these rails from the guide rails 5 and 7, respectively. The plate 8 is fastened, by means of a plurality of screws 8^a, to a stringer 9 10 which is secured to the crossties 2 by means of lag screws 20, and the plate 10 is similarly fastened, by means of a plurality of screws 10^a, to a stringer 11 which is secured to the crossties 2 by means of lag screws 21. The 15 heads of the lag screws 20 and 21 are located in suitable holes formed in the plates and the stringers so that the heads of the screws do not extend above the tops of the plates. The parts are arranged in such manner that the upper surfaces of the plates 8 and 10 are level with the tops of the track rails 1 and 1^a as best seen in Fig. 2.

A plurality of bolts 16, here shown as two in number, extend through the guide rail 5, 30 block 13, track rail 1, and stringer 9, and two similar bolts 17 extend through the guide rail 7, block 15, track rail 1^a, and stringer 11, to hold the parts in their proper positions.

When the car wheels of a car are raised 35 from the track rails by the braking bars of the retarder A there are several positions which the wheels may take with relation to the rails and to the retarder itself. For example, when the retarder occupies its closed 40 position, the tread of the one wheel may ride on top of braking bar 4 and the tread of the other wheel may ride on top of braking bar 4^a; or the tread of one wheel may ride on top of an outside braking bar 4 or 4^a while tread 45 of the other wheel remains on its track rail or again, when the retarder occupies either its open or closed position, the tread of one wheel may ride on top of an outside braking bar such as 4 and the flange of the other wheel 50 on top of an inside braking bar such as 3^a.

In explaining the operation of the apparatus, I will assume that the wheels of a car occupy the positions last mentioned above. Under these conditions, after the car wheel whose flange has been riding on top of the braking bar 3^a rolls off of the end of the braking bar, the flange of this wheel rides on plate 55 14. As it continues its forward motion, the flange engages the leg 7^a of the guide rail 7 which guides the wheel back to its proper position with relation to the rail 1^a. The opposite wheel which in the meantime has had its tread riding on braking bar 4 drops onto plate 8 after leaving the retarder and is guided 60 back to its position on the rail 1 as a re-

sult of the guiding effect imposed upon the opposite wheel by leg 7^a of guide rail 7. The operation of the guide rails for the other positions of the car wheels pointed out above is similar to that just described and will be readily understood from an inspection of the drawing.

Although I have herein shown and described only one form of apparatus embodying my invention, it is understood that various changes and modifications may be made therein within the scope of the appended claims without departing from the spirit and scope of my invention.

Having thus described my invention, what I claim is:

1. The combination with a railway car retarder comprising braking bars located in the trackway adjacent the track rails and movable into engagement with the wheels of a car for retarding the motion of the car, of a rigidly fixed guide rail inclined toward one track rail from a point adjacent the leaving end of a braking bar which is associated with said one track rail.

2. The combination with a railway car retarder comprising braking bars located in the trackway adjacent the track rails and movable into engagement with the wheels of a car for retarding the motion of the car, of a rigidly fixed guide rail inclined toward one track rail from a point adjacent the leaving end of a braking bar which is associated with said one track rail, the top of said guide rail being higher than the top of said one track rail.

3. The combination with a railway car retarder comprising braking bars located in the trackway adjacent the track rails and movable into engagement with the wheels of a car for retarding the motion of the car, of a rigidly fixed guide rail inclined toward one track rail from a point adjacent the leaving end of a braking bar which is associated with said one track rail, and a flat plate extending parallel with and in engagement with the other track rail and having its upper surface level with the top of said other track rail.

4. The combination with a railway car retarder comprising braking bars located in the trackway adjacent the track rails and movable into engagement with the wheels of a car for retarding the motion of the car, of a rigidly fixed guide rail located between said track rails and inclined toward one track rail from a point adjacent the leaving end of a braking bar which is associated with said one track rail, the top of said guide rail being higher than the top of said one track rail, and a flat plate extending parallel with and in engagement with the other track rail on the opposite side of said other track rail from said guide rail and having its upper surface level with the top of said other track rail.

5. The combination with a railway car re-

5 retarder comprising braking bars located in the trackway adjacent the track rails and movable into engagement with the wheels of a car for retarding the motion of the car, of a rigidly fixed guide rail located between said track rails and inclined toward one track rail from a point adjacent the leaving end of a braking bar which is associated with said one track rail, the top of said guide rail being higher than the top of said one track rail, a first flat plate located between said guide rail and said one track rail and having its upper surface parallel with the top of said one track rail but located below the top of 15 said one track rail a distance which is slightly less than the minimum depth of a car wheel flange, and a second flat plate extending parallel with and in engagement with the outside of the other track rail and having 20 its upper surface level with the top of said other track rail.

6. The combination with a railway car retarder comprising braking bars located in the trackway adjacent the track rails and movable into engagement with the wheels of a car for retarding the motion of the car, of two guide rails located between the track rails, one inclined toward each track rail from a point adjacent the leaving end of a 25 braking bar at the leaving end of said retarder, the tops of said guide rails being higher than the tops of the track rail, two plates one located between each guide rail and the associated track rail and each having its upper 30 surface parallel with but located below the top of the associated track rail a distance which is slightly less than the depth of a car wheel flange, and two other plates, one located on the outside of each track rail and each having one edge extending parallel with 35 and in engagement with the associated track rail and having its upper surface level with the top of the associated track rail.

7. The combination with a railway car retarder comprising braking bars located in the trackway and movable into engagement with the wheels of a car for retarding the motion of the car, of a guide rail located in the trackway adjacent the leaving end of 45 said retarder for positively guiding onto the rails car wheels which have been raised from the rails during the transit of the car through said retarder.

8. The combination with a railway car retarder comprising braking bars located in the trackway and movable into engagement with the wheels of a car for retarding the motion of the car, of two guide rails rigidly fastened in the trackway at the leaving end 50 of said retarder and one adjacent each track rail for positively guiding onto the rails car wheels which have been raised from the rails during the transit of the car through said retarder.

9. The combination with a railway car re-

5 retarder comprising braking bars located in the trackway and movable into engagement with the wheels of a car for retarding the motion of the car, of a plate located in the trackway adjacent one side of one rail at the 70 leaving end of said retarder to receive car wheels raised from the track rails during the transit of the car through the retarder, and a guide rail adjacent the opposite side of the other rail for positively guiding the 75 wheels of a derailed car onto the rails, said plate permitting transverse movement of one wheel while the wheel on the other end of the same axle is guided onto the rail.

In testimony whereof I affix my signature. 80
HERBERT L. BONE.
